UNITED STATES PATENT OFFICE.

RICHARD HAMMOND, OF BUFFALO, NEW YORK.

MULTIPLE DRILLING-MACHINE.

SPECIFICATION forming part of Letters Patent No. 398,962, dated March 5, 1889.

Application filed May 29, 1888. Serial No. 275,428. (No model.)

To all whom it may concern:

Be it known that I, RICHARD HAMMOND, of Buffalo, in the county of Erie and State of New York, have invented a new and Improved 5 Multiple Drilling-Machine, of which the following is a full, clear, and exact description.

The object of the invention is to provide a new and improved multiple drilling-machine especially adapted for drilling apertures for 10 the rivets in boiler or other plates after the latter are formed and in place, so as to perfectly match the apertures in the plates to be fastened together.

The invention consists of a central drilling-tool and of two outer drilling-tools held parallel with the said central drilling-tool and mounted in bearings held to swing from the said central drilling-tool.

The invention also consists of certain parts 15 and details and combinations of the same, as will be fully described hereinafter, and then pointed out in the claims.

Reference is to be had to the accompanying drawings, forming a part of this specification, 20 in which similar letters of reference indicate corresponding parts in all the figures.

Figure 1 is a side elevation of the improvement as applied, showing the boiler-plates in section. Fig. 2 is a longitudinal sectional elevation of the same. Fig. 3 is an enlarged sectional elevation of the drill-head. Fig. 4 is a plan view, partly in section, of the rear end of the improvement. Fig. 5 is an enlarged sectional end elevation of the improvement 35 on the line $\alpha-\alpha$ of Fig. 2. Fig. 6 is an inverted plan view of the drill-block; and Figs. 7, 8, 9, and 10 show different arrangements of the holes as bored by the machine. Fig. 11 is a side elevation of the improvement as applied.

On the base-plate A are secured the columns B and C, of which the former is provided with its upper end with a head, B', in the top of which is mounted to rotate in suitable bearings the longitudinal driving-shaft D, 40 provided with the usual pulleys, D', connected by a belt with suitable machinery for imparting a rotary motion to the said driving-shaft D. In the middle of the shaft D is secured a pinion, D², meshing into a gear-wheel, D³, provided with a hub, D⁴, mounted to rotate in the bearings B², formed in the middle of the head B'.

The hub D⁴ is provided with a fixed key fitting into a groove, E', formed longitudinally in the drill-shaft E, passing through the said hub D⁴, so that the rotary motion of the gear-wheel D³ is transmitted to the said shaft E, and the latter is at the same time permitted to slide longitudinally in the hub of the said gear-wheel D³. On the outer end of the shaft 55 E is secured the drilling-tool F, of any approved construction, and near the outer end of the said shaft is secured a gear-wheel, G, meshing into the gear-wheels G' and G², secured on the shafts G³ and G⁴, respectively, 60 carrying at their outer ends the drilling-tools F' and F², respectively, held parallel with the central drilling-tool, F, and at equal distances from the same.

The shafts G³ and G⁴ are mounted to rotate 70 in suitable bearings, H and H', respectively, each being made, preferably, in two pieces and in U shape, and having its ends pivoted on the central drill-shaft, E, as is plainly illustrated in Figs. 3 and 5. Thus the bearings H and H' can be turned on the central shaft, E, so that the drilling-tools F' and F², respectively, carried by the said bearings H and H', respectively, will always remain equidistant from the said central drilling-tool, F. 75 The U-shaped bearings H and H' are provided at their middle part with longitudinal bolts J and J', respectively, each having a head, J², passing into an annular groove, K², formed in the face-plate K, provided with a 80 rearwardly-extending hub, K', through which passes the central shaft, E, having a box, L, fitting into the said hub K', and resting on one side of a collar, E², formed on the said central shaft, E. One end of the bearing H', 85 above mentioned, rests on the other side of the said collar E², and the other bearing, H, is prevented from shifting longitudinally by a collar or nut, H², screwing on the front end of the central shaft, E, as is plainly shown in 90 Figs. 2 and 3.

On the outer ends of the bolts J and J' screw the nuts J³, so as to fasten the respective bearings H and H' firmly to the face-plate K by adjusting the said nuts K³. On the 100 sides of the bearings H H' are formed flanges, through which pass additional bolts, H³, extending into the annular slots K², and serving to assist in securing the bearings H H' to

the said face-plate K. The latter is secured by bolts K³ to a collar, N, provided with a hub, N', extending rearwardly concentric with the shaft E and the hub K', before mentioned.

- 5 In this hub N' are formed longitudinal slots N², into which project the keys B⁴, secured on a hub, B³, projecting from the front end of the box B', and arranged concentrically with the bearings D² and the central shaft, E. 10 Thus the hub N surrounds the hub B³, and the latter surrounds the hub K', and through the latter passes the central shaft, E.

On the outside of the hub N' is formed a thread, N³, on which screws a nut, O, provided with a hand-wheel, O', for turning said nut, and the latter is provided with an annular groove, O², formed near its rear end. Into this annular groove O² fits a split ring, P, secured in the bracket P', fastened in any suitable manner to the front end of the head B'. Thus when the hand-wheel O' is turned it imparts a like motion to the nut O, which revolves in the stationary split ring P, so that the hub N' is moved forward or backward 25 longitudinally, according to the direction in which the hand-wheel O' is turned. The outward movement of the hub N causes a like movement of the face-plate K, the shaft E, and the bearings H and H', carrying the drilling-tools F' and F². The hub N' is prevented from turning on account of the stationary keys B⁴ engaging corresponding slots in the said hub N'.

In the column C is held to slide longitudinally a sleeve, C', adapted to be secured at any convenient height by a set-screw, C², screwing into the column C against the outside of the sleeve C'. On the top of the sleeve C' is held to slide forward and backward a frame, Q, carrying in its front end a transverse wooden block, Q', adapted to rest against the inside of the inner plate, R, to be bored and riveted in connection with the plate R', held on the outside of the said plate R.

The plates R and R' form the boiler-shell R², suspended at its upper end on the chains T, secured to a swivel, U, held on the sheave U', supported by the chain U², extending upward and over pulleys on the carriage V, mounted to travel on the frame W, held to travel on tracks supported by the posts W'. One end of the chain U² is secured to a fixed block, U³, held on the frame W, and the other 55 end of the chain U² is connected with a hydraulic ram, U⁴, or other suitable means for raising or lowering the sheave U' and the boiler-shell R².

The carriage V can be moved forward and 60 backward on the frame W by a chain, V', connected with its ends to the said carriage and passing over the pulleys V⁴ and V⁵, mounted on the frame W, and of which one is rotated by a chain or rope, V³, passing over 65 a large pulley on the shaft of the said pulley V⁴.

The operation is as follows: The plates, R and R', to be riveted together are formed in the desired shape, then fitted over each other and temporarily secured in this position by 70 suitable means. The plates R and R' are then passed between the block Q and the drilling-tools F, F', and F², the latter being set to drill apertures in the said plates R and R' and arranged in any desired manner, as 75 illustrated in Figs. 7, 8, 9, and 10—that is, the drilling-tools F, F', and F² may be set directly above each other, as illustrated in Figs. 1, 2, 3, and 5, so as to drill simultaneously three apertures located one above the other in a 80 straight line, as shown in Fig. 9. By loosening the nuts J³ on the bolts J and J' the bearings H and H' may be swung up or down, so as to stand at right angles to each other. Thereby the drilling-tools F, F', and F² can 85 simultaneously form apertures in the plates R and R', as illustrated in Figs. 7 and 8. The bearings H and H', after being swung to the desired position, are again fastened to the front plate, K, by adjusting the nuts J³. The 90 bearings H may also be set so that the drilling-tools F' and F² are above and below the central drilling-tool, F, whereby the three drilling-tools form simultaneously apertures in the boiler-plates R and R', as illustrated 95 in Fig. 10.

The plates R and R', forming the shell, are suspended, as shown and described, and are raised or lowered by the ram U⁴. The shell can be turned the desired distance for drilling 100 a new set of apertures, as the swivel U permits such motion. The carriage V is adjusted on the frame W according to the diameter of the shell R², so as to bring the respective plates R and R' directly out on the block Q'. 105

The rotary motion of the driving-shaft B is transmitted by the pinion D² and the gear-wheel D³ to the central shaft, E, which, by the gear-wheel G, meshing into the gear-wheels G' and G², imparts a rotary motion to the shafts 110 G³ and G⁴, carrying the drilling-tools F' and F², so that the three drilling-tools F', F², and F are rotated simultaneously; but the central drilling-tool, F, rotates in an opposite direction from the drilling-tools F' and F², so that 115 the latter are formed either right and left handed and the central tool left or right handed. The operator then takes hold of the hand-wheel O' and turns the same so as to impart a forward sliding motion by the nut 120 O to the hub N', carrying the face-plate K, on which are secured the bearings H and H', and which face-plate, in connection with the bearings, carries the central shaft, E, forward by means of the collar E², resting between the 125 said bearing H' and the face-plate K. Thus the three drilling-tools F, F', and F² are advanced simultaneously, and also receive a simultaneous rotary motion. The drilling-tools can thus drill into the outer plate, R', 130 and then through the inner plate, R, thus forming three apertures at a time, said aper-

tures being located in such a position in relation to each other as above described in reference to Figs. 7, 8, 9, and 10.

The block Q' in the frame Q is held directly in front of the tools, so that the latter, after boring through the inner plates, R, pass into the said block Q' to prevent the tools from breaking. When the holes are drilled, the operator turns the hand-wheel O' in an opposite direction, so that the drilling-tools F, F', and F² pass out of contact with the plates R and R', after which the said plates are turned, raised, or lowered the required distance, and the above operation is repeated to drill a new set of holes in the said plates. Thus three holes are drilled in the said plates simultaneously, as shown in Fig. 7, 8, 9, or 10, or any other angle. If it is desirable to drill only two holes, any two of the three drilling-tools may be used for this purpose; but when it is desired to drill only one hole, then either one of the three drilling-tools may be used.

I do not limit myself to the peculiar construction shown for raising or lowering the plates R and R', forming the shell R², as any suitable hoisting mechanism can be employed.

I have filed a separate application, Serial No. 275,699, for the method involved in the operation of this machine.

Having thus described my invention, what I claim as new, and desire to secure by Letters Patent, is—

1. In a drilling-machine, the combination, with a central drilling-tool, of two outer drilling-tools held parallel with the said central drilling-tool and mounted in bearings held to swing from the said central drilling-tool, substantially as shown and described.

2. In a drilling-machine, the combination, with a central shaft carrying a drilling-tool, of two outer parallel shafts rotated from the said central shaft and mounted in bearings pivoted on the said central shaft, substantially as shown and described.

3. In a drilling-machine, the combination, with a central shaft carrying a drilling-tool, of two outer parallel shafts, each carrying a drilling-tool and rotated from the said central shaft, and bearings carrying the said outer shafts and pivoted on the said central shaft, substantially as shown and described.

4. In a drilling-machine, the combination, with a face-plate, of a central shaft held to rotate in the said face-plate and carrying a drilling-tool, two outer parallel shafts, each carrying a drilling-tool and rotated from the said central shaft, and bearings carrying the said outer shafts pivoted on the said central shaft, said bearings being adapted to be se-

cured to the said face-plate, substantially as shown and described.

5. In a drilling-machine, the combination, with a face-plate mounted to slide forward and backward, of a central shaft passing through the said face-plate and carrying a drilling-tool, two outer parallel shafts, each carrying a drilling-tool and rotated from the said central shaft, and bearings carrying the said outer shafts and pivoted on the said central shaft and adapted to be secured to the said face-plate, substantially as shown and described.

6. In a drilling-machine, the combination, with a face-plate and means, substantially as described, for imparting a forward and backward sliding motion to the said face-plate, of a central shaft passing through the said face-plate and carrying a drilling-tool, two outer parallel shafts, each carrying a drilling-tool and rotated from the said central shaft, and bearings carrying the said outer shafts and pivoted on the said central shaft and adapted to be secured to the said face-plate, substantially as shown and described.

7. In a drilling-machine, a face-plate mounted to slide forward and backward and provided with an annular slot, in combination with a central shaft mounted to rotate in the said face-plate and sliding forward and backward with the same, two outer parallel shafts rotated from the said central shaft, bearings carrying the said outer shafts and pivoted on the said central shaft, and bolts passing into the said annular slots and through the said bearings to secure the latter to the face-plate, substantially as shown and described.

8. In a drilling-machine, a face-plate mounted to slide longitudinally, a central shaft mounted to rotate in and sliding with the said face-plate, two outer parallel shafts rotated from the said central shaft, and bearings carrying the said outer shafts and pivoted on the said central shaft and connected with the said face-plate, and drilling-tools secured to the said central and outer shafts, in combination with a wooden block held in front of the said drilling-tools, a frame carrying the said block and mounted to slide horizontally, a table in which the said frame is held to slide, a sleeve carrying the said table, and a column in which the said sleeve is held vertically adjustable and mounted to turn, substantially as shown and described.
